UNITED STATES PATENT OFFICE.

DANIEL M. COOPER, OF ROCHESTER, NEW YORK, ASSIGNOR, BY MESNE ASSIGNMENTS, TO AMERICAN LAUNDRY MACHINERY COMPANY, OF CINCINNATI, OHIO, A CORPORATION OF OHIO.

PRESSING-MACHINE.

1,069,232.

Specification of Letters Patent.

Patented Aug. 5, 1913.

Application filed December 23, 1909. Serial No. 534,715.

To all whom it may concern:

Be it known that I, DANIEL M. COOPER, of Rochester, in the county of Monroe and State of New York, have invented certain 5 new and useful Improvements in Pressing-Machines; and I do hereby declare the following to be a full, clear, and exact description of the same, reference being had to the accompanying drawings, forming a part of this specification, and to the reference-numerals marked thereon.

The present invention relates to pressing machines of the type in which a pair of members are movable relatively one toward 15 and from the other for the purpose of pressing material between them, and an object of the invention is to provide a construction by which a very great pressure may be obtained without the use of motive power.

20 Another object of the invention is to provide a pressure applying mechanism which is durable in use, simple in operation and inexpensive to manufacture.

Still another object is to improve that 25 type of pressing machine in which a work support is mounted to move into and out of vertical alinement with the pressing head, a novel means being provided for stopping the work support when it is alined with the head, and novel means being also employed 30 for releasing the work support after the pressing operation.

To these and other ends the invention consists in certain improvements and combinations of parts, all as will be hereinafter more fully described; the novel features being pointed out in the claims at the end of the specification.

In the drawings: Figure 1 is a front elevation of the machine constructed in accordance with this invention, parts being broken away, and other parts being illustrated in section; Fig. 2 is an end elevation with parts broken away and parts in section; Fig. 3 is a section on the line $a-a$ of Fig. 2; Fig. 4 is a vertical section of the base of the machine showing the mechanism for effecting the relative movement between the work support and the presser head, and Fig. 5 is a detail 45 view of the locking device which holds the work support in vertical alinement with the presser head.

The invention is, in this instance, em-

bodied in a pressing machine for pressing or ironing wash goods, such for instance as 55 shirt bosoms or other similar flat work, but it will be understood that the improvements are capable of being embodied in any pressing machine operating upon a similar principle.

60 The present embodiment comprises a hollow base 1 having integral arms 2 extended outwardly from its upper end and supporting upright rods 3 whose upper ends carry a frame 4 having arranged on its under side a 65 presser head 5 which in this instance is heated by any suitable means.

Mounted to turn upon one of the upright members 3 is a supporting member having one or more supporting arms 6 near the 70 outer end of each of which is provided a vertical bearing or guide 7. In this guide works a depending portion 8 on the work support 9 which in this instance is padded as at 10. The work support is prevented 75 from turning in the guide 7 by a parallel guide member 11 working in the guide sleeve 12 on the arm 6, a spring 13, if desirable, acting between the work support and its supporting arm 6 to prevent any binding action 80 in the guide 7, due to an unequal distribution of weight on the work support.

85 The pressure applying mechanism or mechanism for effecting the relative movement between the work support and the presser head comprises preferably a toggle consisting of link members 14 and 15 arranged within the hollow pedestal or base 1. The upper toggle member 14 of this toggle is pivoted at 16 preferably to the swinging 90 member 17 that is pivoted at 18 at one side of the longitudinal axis of the toggle and cooperates with that portion 8 of the work support depending through the bearing 7. By connecting the upper end of the toggle 95 to the swinging member greater strength and life for the machine is obtained and the cost of a great deal of machine work eliminated. The pivoted member 17 may have guided thereon an adjustable wedge piece 100 19 which increases the effective length of the toggle and is adjusted by any suitable means, as by the screw 20 turning in the wedge piece and engaging threads in the pivoted member.

105 The toggle is straightened by any suitable

means but it is preferred to employ a manually operable lever 21 pivoted to the frame of the machine at 22 independently of the toggle and having a link 23 pivoted thereto and to the joint 24 of the toggle. It is apparent that when this lever is moved in one direction it will straighten the toggle and cause the pivoted member to swing upwardly and force the work support toward the presser head 5. Of course, on the movement of the lever in the other direction the joint of the toggle will be broken and the work support will lower under its own weight. The lever 21 is held in both positions by a dog 47 slidably arranged on the lever, controlled by a hand piece 47^a and adapted to enter notches 48 and 49 on a rack or segment 50. This segment also carries a stop 51 to limit the outward movement of the lever 21 and toggle. The inward movement of the toggle is limited by cooperating stops 52 and 53 formed on the members 14 and 15 in proximity to the toggle joint.

Ironing machines of the press type are usually controlled or operated by girls, and the latter have not sufficient strength to effect a proper pressing of the goods with a single toggle. In this invention in order to obtain greater pressure, there has been combined with a toggle, a swinging member 25 pivotally supported at its lower end, as at 26, and having its upper end pivotally connected as at 27 with the lower end of the lower toggle member 15 so as to form a toggle with said lower toggle member. This toggle preferably breaks in a direction opposite to that of the toggle formed by the members 14 and 15 so that each toggle may operate without affecting the other. It is preferred to make the lower link or member 25 of less length than either the member 14 or the member 15 so that greater power may be obtained from the lower toggle. The latter is straightened preferably by an arm 28 rigid with the lower end of the member 25, being extended forwardly from the rock shaft 26 that forms the pivot of the member 25 and provided with a treadle 29 at its outer end. Stops 54 and 55 formed on the members 15 and 25 may limit the inward movement of the lower toggle and an arm 30 may be extended from the rock shaft 26 rearwardly to coöperate with the yielding stop 31 on the frame in order to limit the outward movement of said lower toggle. The shaft 26 may also have a weighted arm 100 extended rearwardly therefrom to counterbalance the treadle lever.

To effect the breaking of the toggle joint 27 the base 1 has pivotally mounted thereon at 32 a lever treadle 33 whose rear end 34 coöperates with the arm 28 in advance of the rock shaft 30 so that when the forward

end of the treadle 33 is depressed the latter will coöperate with arm 28 at its rearward end to elevate the said arm 28 and throw the upper end of the member 25 to the rear, thus breaking the lower toggle.

It is desirable to lock the work support in vertical alinement with the presser 5 during the movement of the work support toward the presser and to this end a locking plunger 35 may be guided on the pedestal or base frame 1 and is pressed upwardly by a helical spring 36. Its upper end 37 is adapted to enter a notch 38 in the arm 6 and in order to guide the locking plunger to the notch an inclined surface 39 is provided on the arm and leads to the notch on one side thereof, while on the opposite side of the notch is arranged a stop 40 which contacts with the end of the plunger and prevents the arm 6 from passing the plunger when the latter is projected. Of course, the plunger may be drawn out of the notch 38 and passed beneath the stop 40 and to this end the lower end of the plunger 35 is engaged by an arm 41 on the rock shaft 42 which also carries an arm 43 connected by a link 44 with the rear end 34 of the treadle 33, lost motion being permitted between the treadle and the link 44 by means of a slot 45 in the link receiving a pin 46 on the treadle. With this arrangement, the lever of the treadle 33 may be depressed to break the lower toggle without affecting the locking device for the work support, but a further movement of the treadle may be employed for operating the locking device and thus an additional controlling device for the locking device is not necessary.

In operation, the work is placed upon the work support 9 preferably while the latter is out of alinement with the presser 5. The work support is then moved into vertical alinement with the presser and is automatically stopped and locked in this position by the spring-pressed locking plunger 35. The operative now moves the lever 21 toward the machine and the movement straightens the toggle formed by the members 14 and 15 and causes the work to be placed under an initial pressure. A pressure now placed upon the treadle lever 28 will straighten the toggle formed by the members 15 and 25 and give a very great pressure upon the work. After the work has been subjected to the desired pressure, the treadle 33 is slightly depressed to break the joint 27 and the lever 21 then moved in a direction away from the machine, thus breaking the joint 24. A further depression of the treadle 33 releases the work support and permits the latter to be shifted transversely of its line of movement toward the presser 5.

A machine constructed in accordance with this invention makes it possible to obtain very great pressure upon the work with very

little effort or energy being exerted by the operative. The movement to and from pressing position is quickly obtained and the parts for accomplishing it are few and not liable to breakage. The positioning of the work support in vertical alinement with the presser 5 is automatically effected and the locking thereof is also obtained by an automatic operation. The locking device is controlled by a member which also controls another part of the machine, thus making unnecessary the provision of an additional controlling element, and the release of the work support by the locking device cannot be effected except upon the reduction of pressure upon the work.

I claim as my invention:

1. The combination with two relatively movable members between which the material is pressed, of mechanism for effecting the relative movement of the members comprising a toggle, means for operating said toggle, a member pivotally connected to and supporting one of the toggle members and forming a toggle therewith, and means for operating the last named toggle.

2. The combination with two relatively movable members between which the material is pressed, of mechanism for effecting the relative movement of the members comprising a toggle, a lever pivoted independently of the toggle members and having connection with the knuckle of the toggle, a member pivotally connected to and supporting one of the toggle members and forming a toggle therewith, and means for operating the last named toggle.

3. The combination with two relatively movable members between which the material is pressed, of mechanism for effecting the relative movement of the members comprising a toggle, means for operating said toggle, a member pivotally connected to and supporting one of the toggle members and forming a toggle therewith, and an arm rigid with said last named member for operating the second named toggle.

4. The combination with two relatively movable members between which the material is pressed, of mechanism for effecting the relative movement of the members comprising a toggle, manually operable means for operating said toggle, a member pivotally connected to and supporting one of the toggle members and forming a toggle therewith, and an arm rigid with said member formed with a treadle at its free end.

5. The combination with two relatively movable members between which the material is pressed, of mechanism for effecting the relative movement of the members comprising a toggle, means for operating said toggle, a member pivotally supported and having pivotal connection with one of the toggle members, said member having less

length than the toggle members and forming a toggle with the toggle member to which it is connected, and means for operating the last named toggle.

6. The combination with two relatively movable members between which the material is pressed, of mechanism for effecting the relative movement of the members comprising a toggle, means for operating said toggle in one direction to break the joint, a member pivotally connected to and supporting one of the toggle members and forming a toggle therewith, and means for operating the last named toggle in a direction opposite to that effected by the first-named toggle-breaking means for the purpose of breaking the last mentioned toggle.

7. The combination with two relatively movable members between which the material is pressed, of mechanism for effecting the relative movement of the members comprising a toggle, a lever pivoted independently of the toggle members and having connection with the knuckle of the toggle, a pivotally supported member having pivotal connection with the lower end of the lower toggle member and forming a toggle therewith, said member being less in length than the length of the toggle member, and an arm rigidly secured to the pivotally supported member.

8. The combination with two relatively movable members between which the material is pressed, of mechanism for effecting the relative movement of the members comprising a toggle, means for operating said toggle, a pivotally supported member pivotally connected to the lower end of the lower toggle member and forming a toggle therewith, an arm having a treadle at its outer end and rigidly secured to the lower end of the pivotally supported member, and an independently pivoted treadle coöperating with said arm to break the toggle between the pivotally supported member and the lower member of the first named toggle.

9. In a pressing machine, the combination with a frame, a platen and a pressing head, said platen and pressing head being movable relatively one to the other, of a treadle operated lever pivoted on the frame, a toggle for operating the movable part journaled on said lever and a hand operated lever pivoted on the frame and connected to the toggle, said hand operated lever and treadle operated lever being adapted to be actuated in the order named to first straighten the toggle and subsequently apply increased power thereto.

10. In a pressing machine, the combination with a platen, and a pressing head, of a three link toggle for moving one of said parts relatively to the other, and separate hand and foot levers acting upon different parts of the toggle to control its operation,

means for locking the hand lever in operated position and a treadle operated trip for breaking the toggle.

11. The combination with a head and a work support, of a supporting member for the work support mounted to carry the latter into and out of vertical alinement with the head, a locking device for holding said supporting member so that the work support is alined with the head, mechanism for moving the work support toward the head embodying a toggle and a treadle for straightening the toggle, and an independently mounted treadle for breaking the toggle having connection with the locking device to release the supporting member.

12. The combination with a head and a work support, of a supporting member for the work support mounted to carry the latter into and out of vertical alinement with the head, a locking device for holding said supporting member so that the latter is alined with the head, mechanism for moving the work support toward the head, and a member for controlling said mechanism having a lost motion connection with the locking device to operate the latter after the

movement to control said mechanism has been made.

13. The combination with a head and a work support, of a supporting member for the work support mounted to carry the latter into and out of vertical alinement with the head, a locking device for holding said supporting member so that the latter is alined with the head, mechanism for moving the work support toward the head embodying a toggle and a treadle for the toggle, and a second treadle coöperating with the first named treadle and having a lost motion connection with the locking device.

14. In a pressing machine, the combination with a frame, a platen and a movable pressing head, of a treadle lever journaled on the frame and movable vertically, and a hand operated lever journaled on the frame and movable toward and from the operator, of a toggle for operating the platen pivotally carried on the treadle lever and a link connecting the hand lever and toggle.

DANIEL M. COOPER.
